UNITED STATES PATENT OFFICE.

OWEN J. McGOWAN, OF BROOKLYN, NEW YORK.

ENGAGING AND DISENGAGING GEAR FOR SHIPS' BOATS.

1,403,798.

Specification of Letters Patent. Patented Jan. 17, 1922.

Application filed April 1, 1921. Serial No. 457,759.

To all whom it may concern:

Be it known that I, OWEN J. McGOWAN, a citizen of the United States, and a resident of the borough of Brooklyn, city of New York, in the county of Kings and State of New York, have invented certain new and useful Improvements in Engaging and Disengaging Gears for Ships' Boats, of which the following is a specification.

10 This invention relates to improvements in engaging and disengaging gear for ships' boats.

One of the objects of this invention is to provide an engaging and disengaging gear 15 for ships' boats comprising an automatically-releasable hook composed of a body portion, and a weighted bill portion in combination with a shackle, adapted to suspend the weight of a boat from the hook, and

20 means associated with the shackle preferably comprising a segmental locking bolt pivoted on the shackle ring for locking the weighted bill of the hook against automatic releasing.

Another object of my invention is to enable 25 the locking of a hook attached to the falls by means of locking device associated with or pivotally connected to the shackle.

Another object of my invention is to provide 30 such a hook and locking means at opposite ends of a life boat, in combination with means within the body of the life boat for simultaneously releasing the locking means for the hooks at opposite ends; whereby such hooks will be prepared for automatic 35 action and will be caused, immediately the load is relieved therefrom, to automatically release and disengage the shackle and thus disconnect the life boat from the falls, and this unlocking and automatic releasing

40 may, if desired, be accomplished simultaneously at the time the load is relieved from the hook but complete disconnection of the shackle cannot be accomplished prior to the relief of the hook from the load as for example 45 when the boat carried by the hooks is waterborne.

With these and other objects in view, the invention comprises the combination of members and arrangement of parts so combined 50 as to co-act and cooperate with each other in the performance of the functions and the accomplishment of the results herein contemplated, and comprises in one of its adaptations the species or preferred form 55 illustrated in the accompanying drawings, in which:—

Fig. 1 is a side elevation of a life boat, partially broken away, and mounted in a pair of davits by means of hooks, shackle and locking means embodying my invention;

Fig. 2 is an enlarged side elevation of a releasing hook and shackle in locked position;

Fig. 3 is a similar view of the hook and shackle after the same have been disengaged;

Fig. 4 is a front end elevation of the hook in locked position as shown;

Fig. 5 is a section on the line 5—5 of Fig. 2;

Fig. 6 is a section on the line 6—6 of Fig. 70 1; and

Fig. 7 is a section on the line 7—7 of Fig. 6.

Referring now to these drawings, which illustrate a preferred embodiment of my invention, 1 and 2 indicate a pair of davits of any suitable construction from the upper ends of which is suspended a life boat 3 by means of falls 4 and an engaging and disengaging gear 5 embodying my invention, 75 part of this gear being, as illustrated, connected to the shackle on the boat and part of it being suspended from the rings 6 of the falls 4. As illustrated, each of the engaging and disengaging gears comprises a swivelled 85 hook member 7 attached to the falls and a pivoted shackle member 8 comprising an avoidal ring attached to the boat and adapted to swing over the hook member and connect the falls to the life boat and suspend 90 the latter from the davits.

Each of the hooks, which are similar in construction, comprises a body portion 7, preferably shaped as shown, with a stop fin 10 and a hook-seat 11. A bill portion 12 95 is pivoted at 9 on the outer edge of the body 7 and has at one side of the pivot 9 a curved tail-portion 13 adapted to fit over and abut against the hook-seat 11 of the body. The outer end of the bill at the opposite side of the pivot 9 is weighted to cause the tail portion 100 when unloaded and otherwise unrestrained to swing out of its seat and into substantially vertical position, but when a boat or other load is suspended from the 105 hook the shackle ring will overlie the tail portion of the bill which will be retained in contact with the seat of the hook against the action of the weighted bill and so long as the load acts upon the tail portion the 110 shackle ring will be securely held in engagement, but, so soon as the weight of the load

is relieved from the hook, the weighted bill portion will cause a disengagement or releasing of the shackle from the hook, the weighted bill swinging downwardly and 5 causing the tail portion to swing on its pivot and eject the ring from its seat on said tail portion. This leaves the boat or other load free from engagement.

In accordance with the present invention, 10 a hook of the type above specified is securely locked or fastened against such automatic releasing action by fastening means until the same is manually unfastened or unlocked. This fastening means is mounted 15 in association or connection with the shackle ring 8. As shown, said fastening means comprises a segmental block 14 swinging on a pivot 15 on the shackle ring 8. This fastening preferably is formed in the shape 20 of a segment and fits when the parts are assembled in engaged position into an opening provided therefor beneath the hook seat in the body portion of the hook, and preferably has a depending bolt portion 14^a 25 which extends downwardly on the side of the shackle ring 8 opposite to that on which it is pivoted and into abutment with the fin of the body portion, so that when the bill is raised and the shackle ring seated upon 30 the tail portion thereof, the fastening segment may be moved pivotally beneath the body portion to lock or fasten the shackle ring 8 to the said body portion 9. The said 35 fastening segment also preferably has an upwardly-extending lever-arm 16 adapted to engage the lower end of the weighted bill portion of the hook to more securely lock the parts against automatic releasing action. The engaging or abutting portion of said 40 lever arm 16 is preferably provided with a spring-pressed latch 16^a of any suitable form to latch together the abutting end of said upwardly extending arm and an abutment 17 formed on the lower surface of the bill. 45

It will be obvious when the locking segment and its arm is thus swung into engagement with the body and bill portions, respectively, of the hook, the shackle ring will be securely fastened or locked in place on 50 the hook and said hook will be locked against automatic releasing action.

Means is preferably provided within the boat for enabling the simultaneous unlocking or unfastening of the fastening members 55 for both hooks, and for this purpose I provide ropes 18 and 19 each connected at one end to the upwardly-extending lever-arm 16 of the fastening segmental block 14, said ropes being suitably guided or led toward 60 the middle of the boat and each having its opposite end connected to a winding drum 20 pivoted in any suitable position within the boat. Said winding drum is, as illustrated, provided with a handle 21 whereby 65 a turning of the drum in one direction will

cause a simultaneous pulling of opposite ropes to cause the segmental fastening blocks to be withdrawn from engagement with the body and bill portions respectively of said hook, whereupon the said hooks at opposite 70 ends of the boat will be simultaneously prepared for automatic action as soon as the weight of the boat is relieved therefrom. This relief of the load will, of course, occur when the boat is waterborne. When the 75 boat is so waterborne, the weighted end of the bill 12 will, immediately upon the weight of the load being relieved from the tail portion, swing downwardly and cause an ejection of the shackle ring 8, and thus automatically disengaging the boat from the falls at both ends simultaneously. To engage the hook with the shackle again, it is only necessary to swing the shackle ring over the bill 80 portion and lift the same to cause the tail portion to seat upon the hook seat in the body portion and then to fasten or lock the shackle in place by swinging the segmental fastening block into place beneath the body and bill portions respectively. The 85 hook will thereupon be securely fastened or locked in engagement with the shackle.

This fastening of the hook against releasing action enables the gear to be handled with much greater facility and much greater 95 security than heretofore besides enabling the releasing of the hooks on opposite ends simultaneously by a single man.

It will be obvious that the manual release of the fastening means may be accomplished 100 at the same time that the boat is waterborne, whereupon the manual release of the fastening means and the automatic release of the shackle by the weighted bill portion of the hook will take place simultaneously.

Having described my invention I claim:

1. The combination with a davit and falls suspended therefrom of a releasing hook connected to said falls; a shackle connected 110 to the boat adapted to engage said hook; means associated with the hook for automatically releasing said shackle from the hook when the weight of the load is relieved from the hook; and means associated 115 with the shackle for fastening said automatic-release means against automatic action and means for unfastening said fastening means.

2. In combination with a pair of davits, 120 each provided with falls and a releasing hook suspended from said falls, shackles mounted on opposite ends of a life boat; means connected with said hooks adapted to cause automatic release of the shackle when the weight of the boat is relieved therefrom; means associated with the shackle for fastening said releasing means against automatic action, and means in the boat for simultaneously unfastening the said locking 125

means at opposite ends of the life boat to prepare both hooks for automatic disengagement.

3. The combination with a davit and falls suspended therefrom, of a releasing hook connected to said falls; a shackle connected to the boat adapted to engage said hook; means associated with the hook for automatically releasing said shackle from the hook when the weight of the load is relieved from the hook; and means associated with the shackle adapted to engage between the hook and shackle ring to lock the ring in its seat in the hook.

15 4. The combination with a davit and falls suspended therefrom, of a releasing hook connected to said falls; a shackle connected to the boat adapted to engage said hook; means pivotally connected with the hook for causing the automatic release of said shackle from the hook when the weight of the load is relieved from the hook; and means associated with the shackle adapted to engage the pivoted releasing means to lock the 25 shackle to the hook.

5. In combination, a davit for raising and lowering ships' boats; falls suspended from said davit; a shackle pivotally mounted in a boat; a hook suspended from said falls comprising a body portion; a weighted bill pivoted to said body and having a tail extending over the body to form a shackle-ring seat and adapted normally to cause an automatic releasing of the hook from the shackle ring; and means having a pivotal connection with the shackle for fastening said ring within the ring seat to prevent automatic action thereof and means for releasing said fastening means.

40 6. In combination, a davit for raising and lowering ships' boats; falls suspended from said davit; a shackle ring pivotally mounted in a boat; a hook suspended from said falls comprising a body portion; a weighted bill pivoted to said body and having a tail extending over the body to form a shackle ring seat and normally cause an automatic releasing of the hook from the shackle; and means associated with the shackle adapted 50 to engage the weighted bill portion of said hook to lock the shackle to the hook.

7. In combination, a davit for raising and lowering ships' boats; falls suspended from said davit; a shackle ring pivotally mounted 55 in a boat; a hook suspended from said falls comprising a body portion having a fin adapted to abut against one side of the shackle; a weighted bill pivoted to said body at the front of the hook above said fin and having a tail extending over the body to form a shackle-ring seat and normally cause an automatic releasing of the hook from the shackle; the said parts being arranged to leave a space between the body portion of the hook and the bottom of

the shackle ring when the same is in engagement with said ring seat, a segmental block pivoted to the shackle ring and adapted to be inserted between the bottom of said ring and the body portion to fasten said body portion to the shaft with the shackle ring in engagement with the ring seat of said weighted bill.

8. In combination, a davit for raising and lowering ships' boats; falls suspended from 70 said davit; a shackle ring pivotally mounted in a boat; a hook suspended from said falls comprising a body portion having a fin adapted to abut against one side of the shackle; a weighted bill pivoted to said body 75 at the front of the hook above said fin and having a tail extending over the body to form a shackle-ring seat and normally cause an automatic releasing of the hook from the shackle; the said parts being arranged to leave a space between the body portion of the hook and the bottom of the shackle ring when the same is in engagement with said ring seat, a segmental block pivoted to the shackle ring and adapted to 80 be inserted between the bottom of said ring and the body portion to fasten said body portion to the shaft with the shackle ring in engagement with the ring seat of said weighted bill; said segmental block having 85 a depending flange adapted to be inserted between the body portion of the hook and to abut against the shackle ring on the opposite side on which the segment is pivoted.

9. In combination, a davit for raising and lowering ships' boats; falls suspended from said davit; a shackle ring pivotally mounted in a boat; a hook suspended from said falls comprising a body portion having a fin adapted to abut against one side of the shackle; a weighted bill pivoted to said body 100 at the front of the hook above said fin and having a tail extending over the body to form a shackle-ring seat and normally cause an automatic releasing of the hook from the shackle; the said parts being arranged to leave a space between the body portion of the hook and the bottom of the shackle ring when the same is in engagement with said ring seat, a segmental block pivoted to the shackle ring and adapted to 105 be inserted between the bottom of said ring and the body portion to fasten said body portion to the shaft with the shackle ring in engagement with the ring seat of said weighted bill; said segmental block having 110 an arm adapted to abut against the under side of the bill to lock the same in raised engaging position; and means within the boat for unfastening said segmental block 115 to prepare the hooks for automatic action.

10. In combination, a davit for raising and lowering ships' boats; falls suspended from said davit; a shackle ring pivotally mounted in a boat; a hook suspended from 120 130

said falls comprising a body portion having a fin adapted to abut against one side of the shackle; a weighted bill pivoted to said body at the front of the hook above 5 said fin and having a tail extending over the body to form a shackle-ring seat and normally cause an automatic releasing of the hook from the shackle; the said parts being arranged to leave a space between the 10 body portion of the hook and the bottom of the shackle ring when the same is in engagement with said ring seat, a segmental block pivoted to the shackle ring and adapted to be inserted between the bottom of said 15 ring and the body portion to fasten said body portion to the shaft with the shackle ring in engagement with the ring seat of said weighted bill, said segmental block having an arm adapted to abut against the under side of the bill to lock the same in raised 20 engaging position; and means for simultaneously releasing said segmental blocks and arms at opposite ends of the life boat to prepare the hooks for automatic action.

25 11. In combination, a davit for raising and lowering ships' boats; falls suspended from said davit; a shackle ring pivotally mounted in a boat; a hook suspended from said falls comprising a body portion having a fin adapted to abut against one side 30 of the shackle; a weighted bill pivoted to

said body at the front of the hook above said fin and having a tail extending over the body to form a shackle-ring seat and normally cause an automatic releasing of the hook from the shackle; the said parts being arranged to leave a space between the body portion of the hook and the bottom of the shackle ring when the same is in engagement with said ring seat, a segmental block pivoted to the shackle ring and adapted to be inserted between the bottom of said ring and the body portion to fasten said body portion to the shaft with the shackle ring in engagement with the ring seat of 40 said weighted bill, said segmental block having an arm adapted to abut against the under side of the bill to lock the same in raised engaging position; connections with arms at the opposite ends of the life boat extending to a common point within the life boat, and means for simultaneously pulling such connections to release the fastening segmental block and arms to prepare the hooks at 45 opposite ends for automatic action.

In witness whereof, I have signed my name to the foregoing specification in the presence of two subscribing witnesses.

OWEN J. McGOWAN.
